UNITED STATES PATENT OFFICE.

FRANK WILLIAM GRADY, OF LOS ANGELES, CALIFORNIA.

ELEVATOR LINK FOR SUCKER RODS.

Application filed March 26, 1927. Serial No. 178,755.

This invention has reference to a link especially designed for use in connection with well tubing elevators, the primary object of the invention being to provide a link 5 of this character wherein the elevator will be evenly balanced to insure a direct pull on the tubing being elevated.

An object of the invention is to provide a link of this character which may be readily 10 and easily connected with the usual tubing elevator without making changes in the construction thereof.

With the foregoing and other objects in view which will appear as the description 15 proceeds, the invention resides in the combination and arrangement of parts and in the details of construction hereinafter described and claimed, it being understood that changes in the precise embodiment of the invention herein disclosed, may be made within 20 the scope of what is claimed, without departing from the spirit of the invention.

Referring to the drawing:

Figure 1 is an elevational view illustrating 25 an elevator equipped with a link constructed in accordance with the invention.

Figure 2 is a plan view of the elevator showing the links in section.

Figure 3 is a perspective view of one of 30 the links.

Referring to the drawing in detail, the reference character 5 designates the elevator which is of the usual and well known structure, the same embodying the usual handle 6, 35 whereby the elevator may be positioned.

Extending laterally from the elevator are spaced ears 7 between which the usual connecting links are supported, and between which the links, forming the subject matter 40 of this invention are held, as clearly shown by the drawing.

The link forming the essence of the invention includes a reduced extension 8 that is of a width to closely fit within the space between the ears 7, the same being provided with an opening 9 for the reception of the pivot pin 10 which also passes through aligning openings in the ears for pivotally connecting the link to the elevator. Means such 45 as cotter keys indicated at 11 are provided at the ends of the pin to prevent the pin from moving laterally through the openings.

The link also includes a pair of spaced ears 12 disposed at right angles to the extension 8, the ears being provided with aligning openings to receive the heads 13 of the link 14 associated therewith, there being provided the pin 15 extending through the openings of the ears and head associated therewith to pivotally secure the link 14 in position. 55

From the foregoing it will be seen that due to this construction, pivotal movement will be permitted between the link and elevator in various directions, so that the elevator 65 will automatically assume a horizontal position to insure a direct pull on the tubing being elevated, thereby facilitating the removal of the tubing. 60

I claim:

1. In combination with a tubing elevator, link members having pivotal connection with the elevator and adapted to swing laterally with respect to the elevator, said link members having spaced ears, said ears of the link 70 members being disposed at right angles to the upper surface of the tubing elevator, and a link having heads positioned between the ears of the link members. 75

2. In combination with a tubing elevator 80 having laterally extended pairs of ears, linkage including link members having extensions fitted between the laterally extended ears, spaced ears on the link members and disposed at right angles to the edges of the 85 extensions, and an inverted U-shaped link having heads fitted between the last mentioned pairs of ears, and forming a part of the linkage.

3. In combination with a tubing elevator 90 having pairs of laterally extended ears, linkage including link members having extensions pivotally mounted between the ears, said members having pairs of upstanding ears, an inverted U-shaped link, means for pivotally connecting the U-shaped link to the last mentioned ears to cause the U-shaped link to swing in a plane at right angles to the movement of the first mentioned link members and at right angles with respect to 95 the elevator. 100

In testimony that I claim the foregoing as my own, I have hereto affixed my signature.

FRANK WILLIAM GRADY.
